FLUE CLEANING MACHINE

Thomas J. Jackson and Joseph Alphonse
Bekemans, Livingston, Mont.

Application September 21, 1932, Serial No. 634,112

2 Claims. (Cl. 29—81)

Our invention relates to flue cleaning machines and has for its object the provision of a highly efficient rotary boiler flue cleaning machine that will remove all lime and scale from a flue without danger of breaking, cracking or otherwise damaging the same and particularly the ends thereof and in which no sanding or bobbing with a hammer is required to complete the cleaning of a flue after having passed through the machine.

To the above end the invention consists of the novel devices and combinations of devices herein-after described and defined in the claims.

In the accompanying drawings, which illustrate the invention, like characters indicate like parts throughout the several views.

Referring to the drawings:

Fig. 1 is a left hand side elevation of the improved flue cleaning machine;

Fig. 2 is a front elevation of the machine with some parts sectioned on the line 2—2 of Fig. 1, on an enlarged scale;

Fig. 3 is a fragmentary view partly in left hand side elevation and partly in vertical section taken on the irregular line 3—3 of Fig. 2;

Fig. 4 is a fragmentary view in rear elevation with some parts sectioned on the lines 4—4 and 4'—4' of Fig. 1 on the same scale as Figs. 2 and 3;

Fig. 5 is a left hand side elevation of the upper breaker, its mounting and the flue, as shown in Fig. 3;

Fig. 6 is a fragmentary detail view of the upper breaker and flue on an enlarged scale;

Fig. 7 is a plan view of the upper breaker and flue, as shown in Fig. 3;

Fig. 8 is a fragmentary detail view principally in section taken on the line 8—8 of Fig. 5;

Fig. 9 is a fragmentary detail view with the carrier shank sectioned on the line 9—9 of Fig. 2;

Fig. 10 is a view principally in rear end elevation with some parts sectioned on the line 10—10 of Fig. 1, on an enlarged scale, and other parts broken away and sectioned; and

Fig. 11 is a fragmentary detail view in section taken on the line 11—11 of Fig. 1, on an enlarged scale.

The frame of the machine includes a rectangular base 12 made up of four plates rigidly connected at their corners by angle bars. The front and back base-forming plates extend above the base 12 and afford frame members 13 and 14, respectively, which are rigidly connected by a tube 15 at substantially the transverse center 55 of the base 12. It will be noted that the end

portions of the tube 15 extend completely through the frame members 13 and 14 and are rigidly secured thereto by welding or otherwise. The frame member 13 is round, except at its junction with the base 12, and the center thereof is at 5 the axis of the tube 15. On the back of the frame member 13, at its perimeter, is a reinforcing flange 16. The tube 15 extends rearward of the frame member 14 and through a hole in a bearing plate 17, at the center thereof. This bearing plate 17 is rigidly secured to the tube 15 by welding or otherwise and is held thereby laterally spaced from the frame member 14.

Removably mounted in the tube 15 is a bushing 18 comprising a tube having on each end a collar 19 which has a working fit with the interior of the tube 15 and holds said bushing centered therein. This bushing 18 is insertable by an endwise sliding movement into the tube 15 from the rear end thereof and the rear collar 19 is provided with an annular external flange 20 which normally engages the rear end of the tube 15 and the bearing plate 17 and limits the movement of the bushing 18 into the tube 15. Any suitable means may be provided for holding the bushing 18 against removal from the tube 15, such as a screw 21, as shown in Fig. 3.

This flue cleaning machine will be provided with a plurality of bushings 18, the collars of which have the same external diameter and the tubes of which will be of different diameters to receive and hold flues of different diameters.

A boiler flue X, to be cleaned, is fed endwise through the bushing 18 from the rear end of the machine and the scale thereon is indicated 30 at Y.

A rack 22, including a rear section and a front section, is provided for holding the flue X as the same is fed into the machine and for receiving the same as it comes out of the machine. Each 40 section of the rack 22 includes a pair of bars 23 which extend parallel to the axis of the tube 15 and are rigidly connected and held edgewise spaced by a plurality of cross-tie angle bars 24. These rack bars 23 are supported on a plurality 45 of leg brackets 25 preferably bolted or otherwise rigidly secured to the floor on which the machine rests. The rear section of the rack 22, at its inner end, is rigidly secured to a fixed angle bar 26 on the outer face of the bearing plate 17 50 and the inner end of the front section of said rack is similarly secured to a fixed angle bar 27 on the outer face of a front bearing plate 28. This bearing plate 28 is rigidly secured to the frame member 13 and held spaced forward 55

thereof and parallel thereto by long bolts 29 and spacing sleeves 30.

Each section of the rack 22 further includes a plurality of pairs of cooperating upper and lower grooved rollers 31 and 32. The lower rollers 32 are between the rack bars 23 and are journaled on fixed axles 33 mounted in depending boxes 34 on the under side of said bars. It will be noted that the axles 33 are held against endwise removal from the boxes 34 by set-screws. The upper rollers 31 are journaled on fixed axles 35 mounted in bearing brackets 36 which rest on the rack bars 23 and are rigidly secured thereto. These bearing brackets 36 have vertical slots 37 through which the end portions of the axles 35 project.

Washers and nuts 38 are applied to the axles 35 outward of the brackets 36. The axles 35, within the slots 37, are flattened on opposite sides, 20 as indicated at 39, to prevent said axles from turning about their axes in the slot 37. The shoulders, formed by the flattened sides 39 of the axles 35, are drawn against the inner faces of the bearing brackets 36 by the nuts 38 and thereby rigidly secure the axles 33 to the bearing brackets 36. Obviously, by loosening the nuts 38 the upper rollers 31 may be vertically adjusted above the lower rollers 32 for flues of different diameters. The slots 37, at their lower 30 ends, have eyes through which the axles 35 may be moved endwise to mount the same in the upper rollers 31 or remove the same therefrom. It will be noted that the rear section of the rack 22, in addition to the pairs of upper and lower rollers 31 and 32, has at its outer end an extra lower roller 32 on which the flue X is first supported for endwise feeding movement between the pairs of rollers 31 and 32.

The rack bars 23 are detachably secured by bolts to the angle bars 24 and 26 and to the leg brackets 25. Blocks or shims 40, of wood or any other suitable material, are removably interposed between the rack bars 23 and the horizontal members of the leg brackets 25 and between said bars and the angle bars 24 and 26. These shims 40, in actual usage of the machine, will be provided in interchangeably usable sets of different thicknesses for use with the bushings 13 for flues of different diameters to support the rack 22 at the proper elevation to hold the flue X axially aligned with the bushing 13.

The greater part of the scale Y is broken and removed from the flue X by a cooperating plurality of rotary breakers 41 in the form of wheels that are forward of the frame member 13. These breakers 41 are radially spaced about the axis of the tube 15 for rotation in a vertical plane that is substantially perpendicular to said axis. Two of these breakers 41, to wit: the lower ones, 60 have their axes in the same horizontal plane below the axis of the tube 15 and the axis of the other or upper breaker 41 is above the axis of the tube 15 and midway between the axes of the lower breakers 41, see Fig. 2.

65 The faces of the breakers 41 are of novel construction, as will hereinafter appear, and each of said breakers is independently driven by a shaft 42 which extends from the rear to the front of the machine. Each shaft 42 includes a rear 70 end section 43, a front end section 44, and two intermediate sections 45. The shaft sections 43 and 44 are telescoped into the intermediate shaft sections 45 which are tubular with freedom for endwise sliding movement. It will be noted that 75 the telescoped portions of the shaft sections 43,

44 and 45 are square in cross-section and connect said sections for common rotation.

The two intermediate shaft sections 45 are rigidly connected by a coupling 46. A gear spindle 47 is connected to the outer end of the shaft 5 section 43 by a universal joint 48 and a breaker spindle 49 is connected to the outer end of the shaft section 44 by a universal joint 50.

The breakers 41 are detachably but rigidly applied to their hubs 51 and which hubs are mounted on the spindles 49 for rotation therewith. Each gear spindle 47 is journaled in a pair of axially spaced bushings 52 mounted in a pair of seats, one of which is in the frame member 14 and the other of which is in the bearing plate 15 17. Each spindle 49, between its breaker 41 and universal joint 50, is journaled in a bushing 53.

Each bushing 53 is mounted in a hub 54 of a breaker carrier 55 and which hubs extend loosely through an inner radial slot 56 in the frame 20 member 13 with freedom for slight angular movement transversely thereof. The slots 56 are spaced circumferentially with respect to the frame member 13 equi-distances apart. A spindle 57, which projects radially from the axis of 25 the tube 15, is rigidly secured to each breaker carrier 55 and journaled in a bushing 58 mounted in the carrier guide 59. The carrier guides 59 have on their backs, at their lower ends, nut-acting lugs 60 which extend into outer slots 61 30 in the frame member 13 outward of the slots 56 and longitudinally aligned therewith. These carrier guides 59 are slidably mounted on the outer face of the frame member 13 and held for straight line sliding movement by guide bars 62 35 fixed on said frame member.

Long thumb-screws 63 are provided for bodily moving the carrier guides 59 radially toward or from the tube 15. These thumb-screws 63 extend, from the perimeter of the frame member 40 13, through the slots 61 and holes in the lugs 60 and have screw-threaded engagement with said lugs. Said thumb-screws 63 are turnably mounted in seats in the frame member 13, at the ends of the slots 61. The heads on the outer ends of 45 the thumb-screws 63 and the nuts 64 applied to the inner ends thereof hold the thumb-screws 63 against endwise movement but with freedom for rotation in their seats and lugs 60.

It is important to note that shoulders on the 50 inner end portions of the two lower spindles 57 and the nuts 65, which are applied to their outer ends, hold said spindles against endwise movement in the respective carrier guides 59. Obviously, the two lower spindles 57 connect the 55 two lower breaker carriers 55 and their carrier guides 59 for common movement whereby the two lower breakers 41 may be adjusted, at will, for flues of different diameters and hold the same in axial alignment with the tube 15. 60

The upper spindle 57 is free for endwise reciprocal movement in the upper carrier guide 59 and permits floating movement of the upper breaker 41, as will presently appear. Reciprocal movement is imparted to the upper spindle 57 by an air cylinder and piston 66 and 67 for moving the upper breaker 41 radially toward or from the projected axis of the tube 15 and for holding said breaker in an operative position with its periphery positioned for engagement with the periphery of the flue X. The rod 68 of the piston 67 is axially aligned with the upper spindle 57 and detachably secured thereto by a nut-equipped bolt 69.

A coiled compression spring 70 is provided for retracting the piston 67, when the air pressure in the cylinder 66 is released, to move the upper breaker 41 radially away from the flue X. This spring 70 encircles the piston rod 68 between the lower head of the cylinder 66 and the piston 67 for compression therebetween. Air under pressure is admitted to the cylinder 66, outward of the piston 67 for operating the same to move the upper breaker 41 toward the flue X, through a pipe 71 leading from a suitable air compressor, not shown. An air regulating valve 72 is interposed in the pipe 71 and an air pressure gauge 73 is also connected to the pipe 71.

15 A three-way valve or other suitable means, not shown, will be interposed in the air pipe 71. This valve, when in position, will admit air to the cylinder 66 to project the piston 67 and when in another position will cut-off the air supply to the cylinder 66 and open said cylinder to the atmosphere to permit the springs 70 to retract said piston. The cylinder 66 and gauge 73 are mounted on a bracket 74 on the frame member 13.

20 Each spindle 57 is normally held from turning about its axis by an angle adjuster 75 which includes a bar 76 that extends transversely of said spindle and has at each end a set-screw 77. The purpose of this angle adjuster 75 is to set the breakers 41 in positions in which they extend at 25 right angles transversely of the flue X or in variable positions in which they extend transversely oblique to said flue, for a purpose that will presently appear. The bars 76 have at their longitudinal centers holes through which the spindles 30 57 project outward of the carrier guides 59. The holes in the bars 76 and the spindles 57, where they pass through said holes, are square in cross-section to connect said bars and spindles for common turning movement about the axes of the 35 spindles 57.

40 The screws 77 have threaded engagement with the bars 76 and are normally held from turning movement by lock-nuts 78. The heads of the screws 77 impinge against the outer face of the frame member 13 and thereby hold the bars 76, and hence the spindles 57, from turning. Obviously, relative adjustment of the screws 77 will move the bars 76 and the spindles 57 about the axes of said spindles and thereby angularly adjust the breakers 41, see Fig. 9.

45 The shafts 42, by which the breakers 41 are rotated, are driven by an electric motor 79 mounted on a base 80 on the left hand side of the machine. The driving connections from the motor 79 to the shafts 42 include a belt 81 arranged to run over a relatively small pulley 82 on the armature shaft of said motor and a relatively large pulley 83 on a shaft 84 journaled in boxes 85 on a front bracket 86 secured to the base 12 and the frame member 13 and a rear bracket 87 secured to said base. A tightener 88 for the belt 81 is secured to the base 12.

50 An intermediate shaft 89 is driven from the shaft 84 by a belt 90 arranged to run over a three step cone pulley 91 on the shaft 84 and a three step cone pulley 92 on the shaft 89. Obviously, these cone pulleys 91 and 92 permit the machine to be operated at three different speeds. The intermediate shaft 89 is journaled in bearings in the frame members 13 and 14 and the plate 17. Keyed to the shaft 94 between the plate 17 and the rear bracket 87 is a relatively small spur gear 93 which meshes with a relatively large spur gear 94. The gear 94 is keyed to a short shaft 95

5 journaled in bearings on the frame member 14 and the plate 17. A relatively small gear 96 is keyed to the shaft 95 and meshes with a loose gear 97 journaled on a flanged bushing 98 on the tube 15. Three relatively small gears 99 keyed 10 one to each of the gear spindles 47 mesh with the loose gear 97 and complete the driving connections from the motor 79 to the shafts 42.

15 The arrangement of the driving connections from the motor 79 to the shafts 42 is such as to 10 rotate the breakers 41 anti-clockwise.

20 Referring now in detail to the construction of the breakers 41 and the action thereof in removing lime and scale from the flue X is as follows: Each breaker 41 has on its periphery a spiral rib 15 100 in the form of a left hand screw thread that extends the full length of said breaker. This rib 100, for instance, may have eight convolutions per inch and is truncated substantially one-half of its width, as indicated at 101. Preferably, 25 the rib 100 is broken or interrupted by corrugating the breaker 41, as indicated at 102. These corrugations 102 have substantially the same depth as the rib 100 and extends at right angles thereto, see Fig. 6. The action of the breakers 25 41 on the flue X rotates the same in the bushing 18 and at the same time, due to the left hand threads 100 and the rotation thereof anti-clockwise, automatically feeds said flue endwise through the machine from the rear to the front 30 thereof. By manipulating the angle adjuster 75 the breakers 41 may be angularly adjusted transversely of the flue X to vary the speed at which said flue is moved endwise. This endwise travel of the flue X may be varied from zero to a pre-determined number of feet per minute, for instance, in the present machine a 2 or 2 1/4" flue 35 may be fed endwise as high as 22' per minute.

40 The action of the interrupted rib 100 on the flue X breaks up the lime and scale thereon both circumferentially and longitudinally thereof and scrape the same therefrom during the compound rotary and endwise travel of said flue.

45 During the travel of the flue X through the machine the same is supported on the two lower breakers 41 and downward pressure is applied to said flue by the upper breaker 41. This pressure on the flue X by the upper breaker 41 may be varied, at will, by adjusting the air regulating valve 72. Obviously, the air pressure in the cylinder 66 on the piston 67 produces an even pressure of the upper breaker 41 on the flue X and will permit said upper breaker to float so that the same is self-adjusted to a flue in case the same is out of round or has uneven places therein. 50 The air in the cylinder 66 acts as a cushion so that the flue X, while being acted on by the breakers 41, will not be cracked, broken or damaged at its ends.

55 By reference to Fig. 6 it will be noted that the receiving ends of the breakers 41 are tapered to facilitate the feeding of the flue X therethrough and the removal of the lime and scale from said flue.

60 To clean the flue X the same is placed on the rear section of the rack 22 and manually fed endwise through the bushing 18 until its front end is between the breakers 41 and at which time the cylinder 66 is open to atmosphere and the upper breaker 41 held raised by the spring 70. 70 With the flue X thus positioned, air is admitted into the cylinder 66 to operate the piston 67 and project the upper breaker 41 onto said flue which starts the rotary and endwise feeding thereof. From the time the upper breaker 41 is brought 75

into contact with the flue X the cleaning thereof and the delivery thereof onto the outer section of the rack 22 is entirely automatic. The rotary movement of the flue X by the breakers 41 will 5 also loosen all sediment and dirt on the inside of said flue.

Any loose dirt or scale on the flue X, after having passed through the breakers 41, is removed by steel wire brushes arranged in two groups 10 in opposing relation for action on opposite sides of the flue X. In one of these groups there are three brushes 103 and in the other group there are four brushes 104. Each group of brushes 103—104 is mounted in a holder 105 on a slide 106 in the form of a flat plate. These slides 106 are simultaneously moved to either project or retract the brushes 103—104 by an air cylinder 109 and a pair of cooperating pistons 110. The cylinder 109 is rigidly secured to the bearing plate 28 above the slides 106. The pistons 110 are arranged in opposing relation and air is admitted to the cylinder 109 therebetween through a branch pipe 111 that leads from the air supply pipe 71.

25. Each slide 106 is connected to one of the pistons 110 by a bell-crank lever 112 intermediately pivoted to the bearing plate 28. The upper or short ends of the levers 112 are connected to the pistons 110 by L-shaped links 113. These links 113 are pivoted to the pistons 110 and work in slots 114 in the cylinder 109 and which slots extend completely through the outer ends of said cylinder. The lower or long ends of the levers 112 are connected to the holders 105 by slot and 30 pin connections 115. Interposed in the branch pipe 111 is a three-way valve 116 which, when in one position, admits air to the cylinder 109, and when in another position, cuts off the air supply to said cylinder and opens the cylinder 40 109 to the atmosphere.

Normally the cylinder 109 is open to the atmosphere and the brushes 103 and 104 retracted but as soon as the front end of the flue X passes between said brushes the operator manipulates 45 the valve 106 to admit air to the cylinder. Air under pressure in the cylinder 109 will move the pistons 110 away from each other and thereby project the brushes 103 and 104 against the flue X on opposite sides thereof with sufficient pressure to remove all scale and dirt therefrom during the compound rotary and endwise travel of the flue X. Obviously the pistons will equalize 50 the pressure of the brushes 103 and 104 on the flue X and thereby hold the same centered.

After the flue X has passed from between the brushes 103 and 104 the operator again manipulates the valve 106 and opens the cylinder 109 to the atmosphere which releases the air pressure on the pistons 110 and thereby permits said 5 brushes to be retracted.

From the foregoing it must be evident that the invention herein disclosed is capable of large range of modification within the spirit of the invention herein disclosed and claimed. 10

What we claim is:

1. In a machine of the class described, means for guiding a flue endwise through the machine, a carrier guide, a scale breaker carrier having a spindle journaled in the guide for turning 15 movement about an axis that extends substantially radially from the axis on which the flue guiding means holds a flue for endwise movement, a rotary scale breaker, a spindle fixed to the scale breaker, journaled in the carrier and extending 20 substantially perpendicular to the first noted axis, means for rotating the breaker spindle, said breaker having spirally arranged teeth, and manually operated means for turning the carrier spindle to adjust the breaker and change the angle 25 of pitch of its teeth with respect to the direction of travel of the flue through the machine, said manually operated means including a bar intermediately fixed to the carrier spindle and set screws in the ends of the bar and engaging the 30 carrier guide as a base of resistance.

2. In a machine of the class described, means for guiding a flue endwise through the machine, a carrier guide, a scale breaker carrier having a spindle journaled in the guide for turning 35 movement about an axis that extends substantially radially from the axis on which the flue guiding means holds a flue for endwise movement, a rotary scale breaker, a spindle fixed to the scale breaker, journaled in the carrier and 40 extending substantially perpendicular to the first noted axis, means for rotating the breaker spindle, said breaker having spirally arranged teeth, and manually operated means for turning the carrier spindle to adjust the breaker and change 45 the angle of pitch of its teeth with respect to the direction of travel of the flue through the machine, said manually operated means slidably engaging the carrier guide as a base of resistance. 50

THOMAS J. JACKSON.
JOSEPH ALPHONSE BEKEMANS.
